UNITED STATES PATENT OFFICE.

SIDNEY A. H. NOEL, OF PENARTH, ENGLAND.

REVERSIBLE STEAM-TURBINE.

1,285,338.

Specification of Letters Patent. Patented Nov. 19, 1918.

Application filed May 3, 1918. Serial No. 232,251.

To all whom it may concern:

Be it known that I, SIDNEY AUGUSTUS HUGH NOEL, subject of the King of Great Britain, residing at No. 24 Archer road,

5 Penarth, in the county of Glamorgan, England, have invented a new and useful Improved Reversible Steam-Turbine, of which the following is a specification.

This invention relates to an improved 10 construction of reversible steam turbine of the type in which there is, in the stator, a succession of closely spaced steam passages through which steam is directed with a tangential velocity-component to impinge on 15 the sides of a succession of closely spaced apertures in a rotor through which it flows to the exhaust passage.

According to the present invention the steam passages to and through the stator 20 are so directed and valve commanded that, for either direction of rotation, the tangential impulse is delivered in such a manner as to be uniformly distributed throughout the circumference of the stator.

25 Also the steam from the stator so impinges on the rotor that the tangential impulse therefrom is uniformly distributed throughout the circumference of the rotor.

The accompanying drawing shows a suitable 30 form of construction embodying the above described invention:

In this drawing:—

Figure 1 is a transverse sectional elevation 35 of the motor, taken along the line 1—1 of Figs. 3 and 5.

Fig. 2 is a transverse section taken along the line 2—2 of Figs. 3 and 5.

Fig. 3 is a longitudinal sectional elevation 40 taken through the axis of the rotor shaft, and

Fig. 4 is an end elevation of the motor.

Fig. 5 is a plan of the valve chest with the cover removed.

In these figures, A is the rotor which is 45 keyed to a shaft B and surrounded by a stator which for convenience is constructed in two parts C and D.

The steam is conducted to a steam-chest 50 G from which its escape to the portions C of the stator is commanded by a slide valve H, the portion D of the stator receiving steam from the same valve-chest G through a slide valve I.

The portion C of the stator has in the 55 right-hand half of its circumference (see

Fig. 1) a plurality of equally spaced passages c^1 so inclined as to direct the steam passing through them to the inclosed rotor A with a whirl in a clockwise direction, there being in the left-hand half of the circumference of C a plurality of passages c^2 so inclined as to direct the steam passing through them to the rotor A with a whirl in an anti-clockwise direction. The annular space c through which the steam flows on 60 its way to the passages c^1 or c^2 is divided into two parts by abutments c^3 , c^4 .

The portion D of the stator has, as shown in Fig. 2, in the right-hand half of its circumference passages d^1 so inclined as to direct the steam passing through them to the rotor A with a whirl in an anti-clockwise direction, there being in the left-hand half of the circumference D passages d^2 so inclined as to direct the steam passing through 65 them to the rotor A with a whirl in a clockwise direction. The annular space d through which the steam flows on its way to the passages d^1 or d^2 is divided into two parts by abutments d^3 , d^4 .

The rotor A is formed with a plurality of 70 equally spaced apertures a throughout its entire circumference, the sides of the apertures being so inclined that the steam delivered from the passages in the surrounding 75 stator impinges nearly normal thereto. The steam, after entering the interior of the rotor, is exhausted therefrom through eduction passages e formed in the casing. The steam which enters the right-hand side of 80 the rotor A, as viewed in Fig. 3, passes to the left-hand side through apertures a^0 and so finds its way to the eduction passages e .

The side-valve H is so constructed that, when it is displaced to the left-hand end of 85 its travel, it opens a way for steam from the steam chest G to the passages c^1 in the portion C of the stator, the way to the passages c^2 being at the same time closed. With respect to the valve I, when it is displaced to 90 the right end of its travel, steam will be admitted to the passages d^2 of the stator D and the way to the passages d^1 will be closed. If therefore the valve H is displaced to the left and the valve I is displaced to the 95 right the portion C of the stator and also the portion D will deliver steam to the rotor with a whirl in a clockwise direction. Accordingly steam will be so directed that a 100 clockwise tangential impulse will be exerted 105 on the rotor. The valve I is so constructed that when it is displaced to the right end of its travel, steam will be admitted to the passages c^2 of the stator C and the way to the 110 passages c^1 will be closed.

in such a manner as to be uniformly distributed throughout the circumference of the stator.

If, in order to reverse the direction of rotation, the valve H is displaced to the right and the valve I simultaneously displaced to the left, a tangential impulse will be uniformly distributed throughout the circumference of the stator and exerted in an anti-clockwise direction.

Also for either direction of rotation, the tangential impulse exerted on the rotor will be uniformly distributed throughout the entire circumference.

Both valves are simultaneously displaced to deliver the steam with either a clockwise or anti-clockwise whirl by means of a double ended lever *h* *i* the arm *h* of which actuates the valve H and the arm *i* the valve I as indicated in Fig. 5. The lever *h* *i* is secured to a spindle which is pivotally mounted in a stuffing box formed in the cover *g* of the steam chest.

A plurality of such turbines may be so inter-connected that the steam is passed suc-

cessively through the series and the entire expansive energy of the steam thereby utilized.

I claim:

A turbine comprising a stator including an inner casing and an outer casing spaced from the inner casing to provide a chamber, said inner casing being formed with four series of passages, abutments dividing said chamber into two compartments and said series of passages into two pairs, the passages of one series of each pair being inclined opposite to the passages of the adjacent series, a rotor within said inner casing and formed with regularly spaced apertures, a chest communicating with said chamber, a pair of sliding valves in said chest for controlling the passage of fluid to one compartment or the other of said chamber, an oscillatory shaft journaled in said chest, and means for operatively connecting said valves and shaft.

In testimony whereof I have signed my name to this specification.

S. A. H. NOEL.
